UNITED STATES PATENT OFFICE.

GEORGE C. WEISS, OF PITTSBURGH, PENNSYLVANIA.

VACUUM-CREATING DEVICE.

1,145,725.

Specification of Letters Patent.

Patented July 6, 1915.

Application filed September 4, 1912. Serial No. 718,474.

To all whom it may concern:

Be it known that I, GEORGE C. WEISS, a citizen of the United States, residing at Pittsburgh, in the county of Allegheny and State of Pennsylvania, have invented new and useful Improvements in Vacuum-Creating Devices, of which the following is a specification.

The invention relates to that class of inventions known as vacuum cleaners, and has for an object to provide a hydraulically operated device for producing suction.

The invention embodies, among other features, a device that is preferably mounted in the cellar or basement of a building and connected with a suitable water supply pipe whereby, through the action of the water in passing through the casing of the device, a sufficient suction will be produced to permit of picking up and carrying away particles of dust or dirt in the other rooms of the house or building, suitable stand pipes being provided for connection with the device in the basement of a building, whereby, through the medium of a hose, access can be had to the nooks and corners of the various rooms, the suction being produced at the nozzle end of the hose and of sufficient strength to take up and carry into the hose through the nozzle end thereof the dirt or dust in the rooms.

In the further disclosure of the invention reference is to be had to the accompanying drawings constituting a part of this specification, in which similar characters of reference designate corresponding parts in all the views, and in which:

Figure 1 is a fragmentary sectional view of a building showing my device mounted in the basement thereof, and having connection with a suitable stand pipe arranged to extend through the building; Fig. 2 is a vertical longitudinal sectional view of the device; Fig. 3 is a front elevation of the device, parts being broken away to disclose the underlying structure; Fig. 4 is a horizontal sectional view taken on the line 4—4 in Fig. 1; Fig. 5 is a horizontal sectional view taken on the line 5—5 in Fig. 1; and Fig. 6 is a horizontal sectional view taken on the line 6—6 in Fig. 1.

Referring more particularly to the views, I employ a tubular casing 10, preferably consisting of a series of connected sections 10^a, 10^b and 10^c, the section 10^a at the upper central end thereof having connection with

a suitable water supply pipe 11, a stand pipe 12 being connected to the section 10^a adjacent the supply pipe 11 and spaced therefrom, the mentioned stand pipe being adapted to extend from one floor to another in a building 13 and provided with a suitable tap 14, one tap being arranged at each floor in order that a hose 15 can be connected to one of the taps 14, said hose being preferably provided with a nozzle 16 at the upper open end of which the suction is produced.

Adjacent the connection of the supply pipe 11 with the section 10^a and in vertical alinement therewith, a frusto-conically shaped nozzle 17 is arranged to depend in the section 10^a, a second nozzle 18 being formed with or suitably secured within the section 10^a at the lower end thereof, at the point where the section 10^a connects with the section 10^b, a similar nozzle 19 being formed with or secured within the section 10^b at the upper end thereof so that the lower end of the nozzle 18 will abut against and aline with the nozzle 19 when the sections 10^a and 10^b are secured in abutting position, each of the nozzles 18 and 19 being frusto-conical in shape and when connected constituting a double nozzle, the mentioned double nozzle being in vertical alinement with the nozzle 17.

The section 10^c consists substantially of a circular casing 20 in which is journaled a paddle wheel 21 having paddles 22 thereof arranged to project into a passage 23 formed in the casing 20, a pipe 24 being provided to connect the sections 10^b and 10^c, said pipe being arranged in vertical alinement with the nozzle 17 and the double nozzle consisting of the single nozzles 18 and 19, a discharge opening 25 being formed in the lower end of the casing 20 and a hood 26 being mounted to contact with a side of the casing and having connection with a tubular extension 27 of the section 10^b, the upper end of the tubular extension 27 being connected with a tubular extension 28 formed with the section 10^a, a series of apertures 29 being provided in a side of the casing 20 to connect the chamber formed by the hood 26 with the chamber formed by the casing 20 as shown in Fig. 3. Suitable valves 30 are mounted on the sections 10^a and 10^b, said valves being manually operable to admit air to the sections 10^a and 10^b for the purpose of increasing or decreasing the suction in the mentioned sections, it being readily ap-

100
105
110

parent that when the valves 30 are open the suction will decrease and when the valves are closed the maximum amount of suction will be produced, it being further seen that the rotation of the paddle wheel 21 in the casing 20 will create a suction in the chamber formed by the hood 26.

In the use of the device described, water is admitted into the casing 10 through the 10 pipe 11 and it will be readily seen that the water will pass through the casing in a continuous stream, this stream being produced and formed by the nozzles 17, 18 and 19 in the casing, it being further seen that 15 the nozzle 17 is spaced from the nozzles 18 and 19 to form passages 10^d between the upper end of the nozzle 18 and the upper end of the casing 10, similar passages 10^e being formed between the lower end of the nozzle 20 19 and the lower end of the casing 10 so that when the stream of water passes through the casing, sufficient suction will be produced at the upper end of the nozzle 16 of the hose 15 to take up any dust or dirt 25 in one of the rooms of the building and convey the same to the casing 10, the suction being sufficient to carry the accumulated dust or dirt through the casing and out through the discharge opening 25, it being further seen that the rotation of the paddle wheel 21 in the casing 20 will produce a suction in the chamber formed by the hood 26 and in the extensions 27, 28 to carry some of the accumulated dust or dirt through the extensions 27, 28 into the hood 26, from which, 35 through the rotation of the paddle wheel 21, the accumulated matter will be carried by the water through the discharge opening 25, a suitable pipe being preferably provided at the discharge opening 25 to connect the section 10^e with a sewer or other waste receiving receptacle.

A device of the character described can be conveniently connected with the usual 40 water supply pipe of an ordinary building

and as disclosed in Fig. 1, the hose 15 can be readily connected to any of the taps 14 for the purpose of taking away the dust or dirt in any one of the rooms of the building, the pressure of the stream of water in passing through the casing 10 being sufficient to produce suction at the passages 10^b and 10^c and in the casing 20 having the paddle wheel 21 therein and the hood 26 connected to the casing 20.

Having thus described my invention, I claim:

1. In a device of the class described, the combination with a casing consisting of a series of connected sections, of a water supply pipe for connection with the casing, a stand pipe for connection with the casing, nozzles independently mounted in the said casing and arranged in vertical alinement with the said water supply pipe, and extensions formed with the said sections, adjacent extensions being connected to form a passage in the said casing, said passage being independent of a second passage formed by the said nozzles in the said casing.

2. In a device of the class described, the combination with a casing consisting of a series of connected sections, of means in the said casing for receiving a stream of water from a supply pipe connected to the casing 75 and conveying the same through the casing, a paddle wheel mounted in one of the sections of the casing and adapted to be engaged by the stream of water to impart rotation to the paddle wheel, and extensions 80 formed on the said sections, adjacent extensions being connected to form a passage from the upper end of the casing to the said paddle wheel.

In testimony whereof I affix my signature 85 in presence of two witnesses.

GEORGE C. WEISS.
